UNITED STATES PATENT OFFICE.

JOHN ANTHONY BILL, OF CINCINNATI, AND CHARLES L. LEWIS, OF TOLEDO, OHIO.

DESIGN FOR A PHOTOGRAPH MOUNTING.

Application filed July 27, 1925. Serial No. 14,230. Term of patent $3\frac{1}{2}$ years.

To all whom it may concern:

Be it known that we, JOHN ANTHONY BILL and CHARLES L. LEWIS, citizens of the United States, residing at Cincinnati and Toledo, in the counties of Hamilton and Lucas and State of Ohio, respectively, have invented a new, original, and ornamental Design for Photograph Mounting, of which the following is a specification, reference

being had to the accompanying drawing, forming part thereof.

The figure is a front elevation of the photograph mounting.

We claim:

The ornamental design for a photograph mounting as shown.

JOHN ANTHONY BILL.
CHARLES L. LEWIS.
